(57) **CLAIM**

The ornamental design for a beverage container cap, as shown and described.

DESCRIPTION

FIG. 1 is a front, top, left isometric view of the new design.

FIG. 2 is a rear, top, right isometric view of the new design.

FIG. 3 is a left side view of the new design.

FIG. 4 is a right side view of the new design.

FIG. 5 is a front view of the new design.

FIG. 6 is a rear view of the new design.

FIG. 7 is a top view of the new design.

FIG. 8 is a bottom view of the new design.

FIG. 9 is a front, top, left isometric view of the new design.

FIG. 10 is a front, top, left isometric view of the new design, with the drink spout cover in a closed position over the drink spout of the cap.

FIG. 11 is a rear, top, right isometric view of the new design, with the drink spout cover in a closed position over the drink spout of the cap.

FIG. 12 is a left side view of the new design, with the drink spout cover in a closed position over the drink spout of the cap.

FIG. 13 is a right side view of the new design, with the drink spout cover in a closed position over the drink spout of the cap.

FIG. 14 is a front view of the new design, with the drink spout cover in a closed position over the drink spout of the cap.

FIG. 15 is a rear view of the new design, with the drink spout cover in a closed position over the drink spout of the cap.

FIG. 16 is a top view of the new design, with the drink spout cover in a closed position over the drink spout of the cap.

FIG. 17 is a bottom view of the new design, with the drink spout cover in a closed position over the drink spout of the cap.

FIG. 18 is a front, top, left isometric view of the new design, with the drink spout cover in a stowed position removed from the drink spout of the cap.

FIG. 19 is a rear, top, right isometric view of the new design, with the drink spout cover in a stowed position removed from the drink spout of the cap; and,

FIG. 20 is a left side view of the new design, with the drink spout cover in a stowed position removed from over the drink spout of the cap.

The broken lines showing portions of a cap, a liquid container, a drink spout cover and a tether are included for the purpose of illustrating environmental structure and form no part of the claimed design.
